EQUIPMENT FOR LOCOMOTIVE FIREBOXES

Chester A. Siegel, Newark, N. J., assignor to
American Arch Company, New York, N. Y., a
corporation of Delaware

Application April 30, 1942, Serial No. 441,181

3 Claims. (Cl. 122—68)

This invention relates to equipment for locomotive fireboxes, and is particularly concerned with a novel arrangement of circulator elements providing not only for improvement in circulation, but also for achievement of certain other objects referred to more fully hereinafter.

In grate-fired coal-burning locomotives, especially where the velocity of the fuel and flame stream is relatively high, a considerable quantity of cinders has been carried upwardly and forwardly over the rear edge of the usual fire arch. This has given rise to a number of difficulties including "cinder cutting" and "flue plugging."

On the one hand, the cinders, being carried in the fuel and flame stream, frequently pass forwardly at the surface of the crown sheet, in consequence of which abrasion of the metal has resulted, in many cases to such an extent that the heads of the crown sheet staybolts are cut away. On the other hand, the carrying of a large quantity of cinders with the fuel and flame stream above the arch and thence forwardly to the flue tubes, has resulted in plugging of flues.

Beyond the foregoing, it may be mentioned that at least a large part of the so-called "cinders" actually comprises burnable fuel which, if retained in the zone of the fire bed for a sufficient length of time, will burn out.

One of the principal objects of the invention is the provision of means for materially reducing the quantity of cinders carried over the arch by the fuel and flame stream, thereby correspondingly reducing the foregoing and other disadvantages.

More specifically, the invention contemplates a novel relative arrangement of water circulator elements and of the fire arch in a manner serving to return cinders to the grate and thereby reducing the quantity of cinders carried over the rear edge of the arch by the fuel and flame stream.

The foregoing is preferably accomplished by employment of a flat bodied circulator element arranged transversely of the firebox at the rear edge of the arch and having an appreciable portion thereof projecting below the plane of the rear edge of the arch. In this way, a baffle action is set up at the rear edge of the arch tending to deflect the cinders downwardly to the fuel bed, as will appear more clearly hereinafter.

How the foregoing and other objects and advantages are attained is fully described with reference to the accompanying drawing, illustrating the preferred embodiment of the invention, and in which—

Figure 1 is a longitudinal vertical sectional view through a locomotive firebox incorporating the improved circulator and arch arrangement of this invention; and

Figure 2 is a transverse vertical sectional view taken substantially as indicated by the section line 2—2 on Figure 1.

The firebox is defined by side sheets 3—3, a crown sheet 4, a throat sheet 5 and an inside back sheet 6. Water space is provided at all of these sides of the firebox by the employment of outside sheets cooperating with the inside sheets just mentioned. Thus, the wrapper sheet 7 overlies the crown sheet and extends downwardly in spaced relation to the side sheets 3. An outside throat sheet 8 cooperates with sheet 5, and an outside back sheet 9 cooperates with sheet 6. Mud ring 10 closes the space between the inside and outside sheets around the edges of the firebox, and the fuel burning grates (not shown) are ordinarily located substantially in the plane of this mud ring. The firebox may be fired either manually or by a mechanical stoker, a fire door being indicated at 11.

At the forward end of the firebox, the flue sheet 12 cooperates with flue tubes 13, only two of which are illustrated, although it will be understood that a multiplicity is ordinarily employed. The flue tubes, of course, extend forwardly through the boiler barrel and usually terminate in the smokebox for discharge of products of combustion through the stack.

At a position well rearwardly in the firebox, a transverse circulator body 14 is arranged, this body being transversely arched, as clearly appears in Figure 2, and having its ends connected with the side water legs. Toward its central or high point, an outlet 15 connects the transverse body with the water space above the crown sheet 4. As illustrated, the transverse body 14 has appreciable side face area, preferably being of flat sided configuration. Stay-bolting 16 may be employed to strengthen the inlet body.

A plurality of circulator tubes 17 (three being shown in Figure 2) interconnects the inlet body 14 of the circulator and the water space at the throat sheet, these tubes being extended downwardly and forwardly from the body 14 so as to provide for support of arch brick 18 constituting a refractory arch. This arch desirably is extended throughout the entire space between the throat sheet and the circulator body 14.

As clearly seen in the drawing, the upper and rear ends of tubes 17 are connected with the circulator body at an elevation above the lower

edge of the body, in view of which the rear edge of the arch formed by bricks 18 is quite high with reference to the lower edge of the transverse body.

With the transverse circulator body 14 located well rearwardly in the firebox, the fuel and flame stream—indicated by the arrows in Figure 1—rising from the major portion of the area of the fire bed (the forward portion) is caused to flow upwardly and thence rearwardly at the under side of the arch 18. At the rear edge of the arch, said stream is deflected downwardly by the lower portion of the transverse circulator body 14, in consequence of which the motion of the cinders initially carried by the stream is broken and/or the cinders are deflected downwardly so that a large proportion of the cinders returns to the fire bed.

The fuel and flame stream bends upwardly and thence forwardly over the arch for entrance into the flue tubes 13.

According to the invention, therefore, the quantity of cinders carried over the arch and along the under side of the crown sheet 4 is very materially reduced, thereby correspondingly reducing abrasion and cutting away of the heads of staybolts, a few of which are indicated at 19. It will be understood that a multiplicity of staybolts is distributed throughout the crown sheet area as well as throughout the areas of the side sheets and other parts of the firebox.

Flue plugging, hereinbefore referred to, is also reduced by virtue of the arrangement described.

Although the transverse circulator body 14 may be located at a point farther forward in the firebox (for instance, as shown in my pending application filed concurrently herewith, Serial No. 441,180), and although the fire arch may extend both fore and aft of this transverse body, the location of said body (as illustrated) well rearwardly in the firebox and at the rear edge of the arch is preferred for the purposes herein contemplated. The location herein disclosed, and especially where a substantial side face area of the transverse body projects below the plane of the arch, is highly effective in deflecting the fuel and flame stream downwardly before it passes up and over the rear edge of the

arch. As a result, the action of throwing the cinders back to the fire bed is at a maximum.

The action just described is further enhanced in the arrangement illustrated by virtue of the fact that the transverse plane in which the body 14 lies is substantially perpendicular to the general plane of the arch, thereby providing an abrupt downward break in the fuel and flame stream at the rear edge of the arch. Projection of tubes 17 perpendicular to the plane of the flattened body 14 also facilitates the making of the tube connections. When arranged in this way, the plane of the body 14 is inclined somewhat forwardly, and in view of this, in order to facilitate making the connection between the outlet 15 and the crown sheet, the upper end of the outlet is preferably bent so as to extend generally perpendicularly to the crown sheet, as clearly appears in Figure 1.

I claim:

1. For a locomotive firebox, circulator equipment comprising a transverse circulator body of appreciable side face area, having its ends connected with the side water legs at a point spaced considerably to the rear of the throat sheet, and a plurality of circulator tubes adapted to support arch brick, said tubes being extended upwardly and rearwardly from the throat sheet and being connected with said body at an elevation appreciably above the lower edge of the body.

2. A construction in accordance with claim 1 in which an outlet element interconnects said circulator body and the crown sheet.

3. For a locomotive firebox circulator equipment comprising a transverse inlet body having its ends connected with the side water legs, a plurality of circulator tubes connected with and extending forwardly and downwardly from said transverse body, said tubes also serving as a circulator inlet and having the forward ends thereof connected with the throat sheet and providing for support of arch brick forming a refractory arch extending upwardly and rearwardly from the throat sheet, and outlet means comprising an element interconnecting said body and the crown sheet.

CHESTER A. SIEGEL.
